Wolait Metal Band Compatible with Apple Watch, available for sale since at least Nov. 30, 2020, online. URL:<"<https://www.amazon.com/Wolait-Stainless-Smartwatch-Compatible-Replacement/dp/B08PBLG94J>"> acquired on Mar. 24, 2022. (Year: 2020).*

Primary Examiner — Llorellys Martinez

(57) **CLAIM**

The ornamental design for a watch band, as shown and described.

DESCRIPTION

FIG. 1 is a perspective view of a watch band showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the watch band that form no part of the claimed design.

1 Claim, 8 Drawing Sheets
